FIG. 1.

FIG. 2.

FIG. 3.

FIG. 4.

Edward C. Walter,
By *E.W. Anderson & Son*,
Attorney

UNITED STATES PATENT OFFICE

EDWARD C. WALTER, OF ORANGE, NEW JERSEY, ASSIGNOR TO MONROE CALCULATING MACHINE COMPANY, OF ORANGE, NEW JERSEY, A CORPORATION OF DELAWARE

DESK STAND

Application filed August 1, 1929. Serial No. 382,639.

The invention has relation to a desk stand for calculating machines, said stand being adapted to be supported upon a desk or table, and having for a primary object to provide a stand so supported with a space directly under the machine which shall be free of all obstructions so that a work sheet, the items of which are to be entered in the calculating machine, may be freely inserted in such space and moved therein in any direction at the will of the operator.

Another object is to relieve the operator of the machine from the necessity of swaying his head sidewise when copying from a work sheet.

Another object is to provide such a space directly below the machine into which a work sheet or book may be placed.

Another object is to provide line and column guides so that copying from the work sheet is facilitated.

Still another object is to provide an adjustment up and down so that the forward edge of the platform may be placed close to the work sheet.

The invention consists in the novel construction and combinations of parts as set forth in the appended claims.

In the accompanying drawing illustrating certain embodiments of the invention, Figure 1 is a side view of the invention, supported upon a desk or table and showing the calculating machine; Figure 2 is a perspective view of the invention; Figure 3 is a side view of a modification showing the adjustment in dotted lines, and Figure 4 is a similar view of another modification, also showing the adjustment in dotted lines.

In the drawing the numeral 1 designates the upper platform of the stand and 2 is the lower platform, spaced from the upper platform and connected thereto in rear by an upstanding or vertical wall 3 in such manner that a calculating machine 4 or the like of comparatively light weight, placed upon said upper platform, shall be properly supported.

The lower platform 2 is adapted to rest upon the desk or table, and the work sheet may be placed between the upper and lower platforms.

The forward horizontal straight edge 6 of the upper platform acts as a guide for the lines of the work sheet and the latter may be moved sidewise to align the columns thereof with the pointer 7, movable along said edge 6.

The space between the upper and lower platforms may be of varying depths and the arrangement provides the operator with means whereby a location on the work sheet may be quickly determined and at such a position that the operator in copying from the sheet to the machine need only raise and lower his eyes from the work sheet to the keyboard of the machine without any turning sidewise of his head.

The work sheet is moved by the operator as the work progresses, from column to column and from line to line, and in doing this should the work sheet be too long, it may be folded or curled up in the space between the platforms.

The pointer 7 is shown as adjustable along the front edge or line guide 6 of the upper platform, so that it may be moved to a position most convenient for the operator; or it may be moved from column to column as the work progresses, instead of moving the work sheet sidewise.

Obviously a book may be used instead of a work sheet and the sheet or book may bear items other than those of a work sheet.

The upper platform is usually only large enough to support a calculating machine of comparatively small size, whereas the lower platform 2 may be larger in area, this being particularly useful in case the stand is supported upon legs rather than upon a desk or table.

Figures 3 and 4 of the drawing show modifications of the invention wherein the upper platform may be adjusted to lower the forward edge thereof until it just clears the work sheet, for the reasons stated.

In these modifications the same reference characters are employed for the same parts, already described, differentiated by the exponent 1 for the first modification and by the exponent for the second modification.

In Figure 3 the upper platform is pivotal-

ly connected to the lower platform at 8 for the purpose stated. An adjustable screw bolt 9 has the stem thereof pivotally connected with the lower platform at 10 and engages a 5 perforation of the upper platform and is provided with a winged nut 11 threaded thereon, so that by turning the nut the upper platform may be lowered and raised, said nut acting as a stop to adjustably limit the downward movement of the platform.

10 In Figure 4 another modification is shown, wherein the lower platform is omitted and the stand is supported from a desk or table by means of a clamp 12 adapted to receive the 15 edge of the desk and having a clamp screw 13. In this modification the clamp 12 is provided in rear with a series of teeth 14, with any one of which the inturned rear hook portion 15 of the platform may be engaged to 20 adjustably limit the downward movement of the platform; and with a forward tooth 16 engaging a seat 17 of the platform. The adjustment is accomplished by lifting the platform 1" off of the supporting clamp 12 and 25 placing the hook portion 15 of the platform in engagement with any one of the teeth 14 and lowering the platform 1" until it rests upon the clamp 12.

While I have shown certain embodiments 30 of my invention, it will be understood that these are for purposes of illustration only, and not intended to limit the scope thereof, for other modifications may be made in the means of dispensing with the lower platform 35 and the means of adjusting the upper platform, without departing from the spirit of my invention.

I claim:

1. In a desk stand for calculating machines and the like, the combination with a 40 lower support, of an elevated platform, said stand having a space between said platform and said support free of all obstructions on three sides thereof and wherein a work sheet 45 may be freely inserted and moved in any direction, said platform having a downturned front straight edge to indicate the line on which the work is being done and provided with a longitudinal slot and a pointer working in said slot and slideable along said edge to indicate the column.

2. In a desk stand for calculating machines and the like, the combination with a lower 55 support, of an overlying elevated horizontal platform, said stand having a space between said platform and said support free of all obstructions on three sides thereof and wherein a work sheet may be freely 60 inserted and moved in any direction, said platform having at the front end thereof a straight line defining edge and at the rear thereof adjustable means of engagement with said support including a stop device adapted 65 to adjustably limit a downward tilting move-

ment of the platform to bring the forward edge thereof closer to the work sheet.

3. In a desk stand for calculating machines and the like, the combination with a lower support, of an elevated platform, said 70 stand having a space between said platform and said support free of all obstructions and wherein a work sheet may be freely inserted and moved in any direction, said platform having a front straight edge line guide and a pointer slideable along said edge, said platform having adjustable engagement with said support and being adjustable downwardly to bring the forward edge of the platform closer to the work sheet.

4. A desk stand for calculating machines and the like having upper and lower platforms, the lower of which is adapted to rest upon a support and the upper of which is adapted to provide a support for the machine, 80 said stand having a space between said platforms free of all obstructions on three sides thereof and wherein a work sheet may be freely inserted and moved in any direction, said upper platform having a downturned front straight-edge line guide provided with a longitudinal slot, and a pointer working in said slot and slideable along said edge to indicate the column.

5. A desk stand for calculating machines and the like, having upper and lower overlying horizontal platforms having a rear connection, the lower of said platforms being adapted to rest upon a support and the upper platform being adapted to provide a support for the machine, said stand having a space between said platforms free of all obstructions on three sides thereof and wherein a work sheet may be freely inserted and moved in any direction, said upper platform having a straight line defining edge at the front end thereof and adjustable means of engagement with the lower platform including a stop device adapted to adjustably limit a downward tilting movement of the platform to bring the forward edge thereof closer to the work sheet.

6. A desk stand for calculating machines and the like having upper and lower horizontal platforms, the lower of which is adapted to rest upon a support and the upper of which is adapted to provide a support for the machine, said stand having a space between said platforms free of all obstructions on three sides thereof and wherein a work sheet may be freely inserted and moved in any direction, 110 said platform having a front straight edge line guide and a pointer slideable along said edge, said platform having adjustable engagement with said support and being adjustable downwardly to bring the forward edge of the platform closer to the work sheet.

In testimony whereof I affix my signature.
EDWARD C. WALTER.
